IRONER

Edwin E. Foster, Austin, Tex., assignor to Majik-Ironers, Inc., Austin, Tex., a corporation of Texas

Application December 14, 1934, Serial No. 757,523
Renewed March 17, 1939

26 Claims. (CL 38—30)

The present invention relates to ironers which are operated mechanically or electrically and mechanically and electrically with the exception of the actual guiding of the iron on the material to be ironed. The subject matter of the present invention constitutes an improvement of applicant's prior ironing devices as disclosed in his prior U. S. applications, Serial Nos. 643,092, 683,218, and 747,241, filed November 17, 1932, August 1, 1933, and October 6, 1934, respectively.

It is an object of the present invention to counterbalance the arm on which an iron is mounted by a simple mechanical means which also acts to provide an ironing pressure on the iron when the iron contacts the material to be ironed. A further object is to provide mechanical and electrical means, and electrical means solely to accomplish the operation just referred to.

Further objects will be apparent from the following description and the accompanying drawings in which the same reference characters indicate corresponding parts and in which:

Figure 1 is a section through the entire ironer with the exception of the lower portion of the legs taken on line 1—1 of Fig. 2.

Fig. 2 is a side view of the entire machine.

Fig. 3 is a top view of the entire machine.

Fig. 4 is a cross-section through the supporting member for the iron taken on line 4—4 of Fig. 5.

Fig. 5 is a longitudinal sectional view of the support and mechanical operating mechanism for the arm and iron.

Fig. 6 is a part sectional view of the support and operating mechanism taken on line 6—6 of Fig. 5.

Fig. 7 is a longitudinal sectional view of the support and operating mechanism showing a modified form in which electrical and mechanical means are shown.

Fig. 8 is a sectional view of the support and mechanism taken on line 8—8 of Fig. 7.

Fig. 9 is a cross-sectional view of the support taken on line 9—9 of Fig. 7.

Fig. 10 is a longitudinal sectional view of the support and electrical operating means of a further modification.

Fig. 11 is a side view of the arm and iron, and Fig. 12 is a side view partly in section of the iron and a portion of the arm on an enlarged scale.

The iron 1 is mounted on an arm 2 which latter is rotatably and movably supported in a support 3. The iron 1 is rotatably mounted on its arm and is capable of turning through 360°. Also

the arm 2 is in two jointed and movable sections 4 and 5, interconnected at the joint 6.

The support 3 includes a box-like casing 7 which is provided with a plate member 8 secured thereto. This casing is secured to a frame 9 by means of two lugs 10 welded or otherwise provided on a frame bar 11. This forms a hinge connection by means of pin 12 which provides the possibility of folding the casing 7, support 3, arm 2 and iron 1 around and under the ironing board 13 by rotating these parts counterclockwise (Fig. 1).

To securely hold the parts in position for use as shown in Fig. 1, the casing 7 is provided with a link 14 pivotally mounted at 15 to the casing 7 and the other end 16 having pivotally mounted thereto a latch member 19. This member 19 has a hook end 18 which grips in the locked position a pin or plate 17 secured in the frame bar 13. The operation of this latch member is obvious and as shown in Fig. 1 the latch is unhooked by merely raising the end 21 of the member 19 which releases the hook end 18 from the pin 17 due to the link 14.

The frame 9 is suitably constructed of tubular bars such as 11 and 18 and tubular legs 22. The bars 23 are part of the frame and are for the purpose of maintaining the board 13 rigid. This board 13 is secured to a suitable base frame 24. Also as seen in Figs. 1 to 3, a cone-shaped element 25 is provided which forms a part of the frame and to which a certain number of the bars and legs are secured as shown. It is obvious that other types of frames and supporting elements may be used and solid bars and rods may be substituted for the tubular members.

The construction shown in Figs. 4 to 6 operates entirely by mechanical elements to counterbalance the iron 1 and arm 2 and to apply an ironing pressure on the iron 1 when the iron has been moved down adjacent the material to be ironed. The arm 2 is secured to a supporting member 26 which slides and rotates in the upper extension 27 of the casing 7 by means of ball bearings 28 of which there are two sets separated by a ball keeper 29. This keeper maintains the proper spaced relation of the sets of balls during their travel vertically upon vertical movement of member 28. A connecting frame 30 is secured to the lower end of the member 26 and moves vertically therewith but permits the rotation of the member 26. A pair of rollers 31 are rotatably mounted on the lower end of the frame 30 by means of shafts 32 which roll on the side 33 of the casing 7. A pair of levers 34, one on each shaft 32, are

5 pivotally mounted at one end on the shafts 32 and the other ends carry a sleeve 35 movable on a shaft 36 pinned on levers 34 as shown in Fig. 6. Two short levers 37 and 38 are rigidly mounted on sleeve 35, lever 37 being connected by lever or connecting link 39 to an adjustable bracket 40, while the other lever 38 has one end of a spring 41 connected thereto. The other end of the spring is connected to one of the levers 34 10 by means of a short rod 42.

10 The adjustable bracket 40 is vertically slidable on the side 33 of the casing 7 by means of the plate 43 riveted or otherwise secured to the side 33. The lower end of the bracket is connected 15 to an adjusting screw 44 having a screw-threaded block 45 secured to the side 33 and bottom 46 of the casing 7. A hand knob 47 is for the purpose of turning the screw 44 to thereby adjust the position of the point 68 vertically to take 20 care of a change in the position of the iron at the exact vertical position where ironing pressure is to be applied.

20 The ball bearing keeper 29 is provided with track groove 48 at the lower end thereof in which 25 a roller 49 travels which is mounted on a rod 50. This rod 50 is slidably guided in a bearing block 51 and is secured to a sleeve 52. The sleeve bears in an elongated slot 53 in each lever 54. Each lever 54 is pivoted to an abutment 55 at one end and the other end is slidably connected to the frame 30 by means of slots 56 in said levers and pins 57.

30 The levers 34 and spring 41 are operated from the iron through the arm 2 by means of rod 58 connected to the levers 34 by means of the connecting means 59. A lever system is provided in the arm 2 as shown in Fig. 11 wherein lever 60 is pivoted at 61 in the section 5, the rod 58 being connected at one end thereof. A rod 40 62 is provided in the joint 6 and is connected to the other end of lever 60. A lever 63 is provided in the section 4 and is pivoted at 64. A short lever 65 connects the lever 63 with the handle 86 of the iron.

40 As shown in Fig. 5 another set of ball bearings 67 is provided at the lower end of the member 26 to permit the latter to rotate. The rollers 31 prevent rotation of the frame 30.

45 The purpose of the levers 37 and 38, which 50 may be termed a compensating device, is to maintain the counterbalancing force as nearly uniform as possible throughout the entire vertical stroke of the iron. The lever 39 will obtain an increasing effective lever arm while the spring 55 41 obtains a decreasing effective lever arm as the levers 37 and 38 are rotated clockwise through 60°.

50 When the member 26 has been pushed down by the hand of the operator through its entire 60 stroke, the pivot point 32 will coincide with the point 68. The iron 1 now contacts the board 13 and a slight push by the operator on the handle 66 pulls the levers 34 upwardly around 32 by means of members 58, 60, 62, 63 and 65. This 65 causes the levers 34 and the spring 41 to pivot upward about 60° thus causing a downward pull on the arm instead of a counterbalancing force.

65 In the construction according to Figs. 7 to 9, 70 the members 26 and 27 are provided with grooves 69 for the balls 28 and the ball bearing keeper 29 is provided with two gears 70 which mesh with two gear racks 71 for each gear. Thereby upon vertical movement of the member 26, the 75 keeper will be in proper position and will main-

tain the balls in their correct spaced relation. As the operation of this construction is for the most part electrical, the arm moves around the member 26, no linkage system passing through the arm, but merely an electrical cable 72. 5

5 In the casing 7, a U-shaped frame 73 is secured to the lower end of the member 26. A spring 74 is secured at one end 75 to the frame 73 and the other end to a lever 76 at 77. This lever 76 is mounted on a sleeve 78 which rotates on a shaft 79. A second lever 80 is secured to the sleeve 78 and is connected to a long link 81 at 82, the link 81 being connected at the other end 83 to the casing 7. This spring 74 serves to counterbalance the weight of the iron 1 and 15 arm 2. An electro-magnet 84 is provided in the bottom of the casing and a second electro-magnet 85 in the frame 73 which are of any suitable construction. The magnet 84 is the pressure magnet and is much larger than the magnet 85. 20 86 is the armature for the magnet 84 and has a plunger 87 connected thereto. Two springs 88 and 89, separated by the member 93 secured to the casing 7, are provided around the plunger 87 and the upper end of the latter projects into 25 and through the frame 73 and cooperates with stops 90 and friction plate 91 secured to the frame 73.

25 The armature 94 for the magnet 85 has a plunger 95 connected thereto which passes 30 through a slot 96 in the plunger 87 and has a wedge cam 97 thereon, the latter being pivoted at 98 in the frame 73. Also springs 99 and 100 are provided around the plunger 95 separated by plate 101 secured in the frame 73. The ring 102 35 is loose on the plunger 95 and bears against the cam 97. A further washer 100 is securely mounted on the plunger 95 and therefore moves with the plunger 95 when the latter moves to the left, Fig. 7, to compress the spring 99. Also 40 when the plunger 95 moves to the right, Fig. 7, the washer 100 acts as a stop against the plate 101 for the plunger. On the end of the plunger an electrical contact arm 103 is secured having a contact 104 cooperating with a contact 105 45 secured on the frame 73, these contacts being in the circuit of magnet 84.

45 Referring to Fig. 12, the iron 1 has an adjusting handle 106 which is secured to a screw-threaded rod 107 which, when they are rotated, 50 adjusts the collar 108 vertically which in turn adjusts the lever 109 and contact member 110. The arm 111 has a rheostat 112 secured thereto which latter is contacted by member 110. Circuit closing contacts 113 are provided, one on the 55 rheostat and one on the arm.

50 In operation, the operator adjusts the handle 106 which adjusts the rheostat to control the strength of the magnet 84. When the operator pushes the iron down the contacts 113 are closed 60 when the iron contacts the material to be ironed, the iron and arm being counterbalanced by the spring 74 so that little pressure is necessary to depress the iron. This energizes the magnet 85 which attracts the armature 94 to pull the cam 65 97 against the plunger 87. This forces the plunger against the plate 91, and the spring 99 against the cam 97 tightly wedges the plunger so that it is securely locked with the frame 73. Then the contacts 104 and 105 close to energize 70 the magnet 84 which then exerts a pull on the arm to effect an ironing pressure on the iron. When the hand is released from the handle of the iron spring 114 against arm 111 breaks contacts 113 de-energizing magnet 85 so that by 75

means of spring 100 the plunger 95 moves to the right breaking contacts 104 and 105 to de-energize the magnet 84 thus permitting the arm and iron to be raised above the board by spring 14. 5 The magnet 85 and associated parts makes the ironing device self-compensating for different thicknesses of material. For instance, if a thin garment is ironed first and then a thick garment, each will have the same ironing pressure 10 applied on the iron.

Springs 88 and 89, Fig. 7, maintain or restore the armature 86 in proper position when the magnet 84 is not energized.

As a direct current is more suitable for use 15 in magnets, a transformer and a rectifier may be used. These may be concealed in a box 115, Figs. 2 and 3, under the board 13.

Fig. 10 shows a construction in which the keeper 29 for the ball bearings 28 is shifted by a 20 rod 50 controlled by lever 54 secured to member 55 similar to Figs. 4 to 6. The member 26, however, has a collar 116 which adjusts the lever 54 upon movement thereof.

Two solenoids, 117 and 118, are provided in the 25 casing 7 cooperating with a core 119 secured on the end of member 26. This operates in such a way that the solenoid 117 is energized to counterbalance the arm and iron, but when the iron contacts the material to be ironed solenoid 117 30 is de-energized and solenoid 118 is energized which supplies the ironing pressure. The control handle 106 is also used to adjust the pressure of the iron by changing the amount of current to solenoid 118 but this does not change 35 the lift of the solenoid 117. The device could also be operated so that solenoid 117 is energized at all times by solenoid 118 being so much larger that it overcomes the pull of the solenoid 117 on the core 119.

40 A bar 121, Figs. 1, 3 and 7, having a fork 122 at one end may be secured to the support 3 for the purpose of preventing the arm 2 from rotating more than 360° to prevent damage to the cord 12 and also to hold the section 4 by means 45 of the fork 122 when the ironer is in a folded position.

The ironer while preferably operated electrically may, however, also be operated by steam, compressed air or any other power medium. 50 This could be simply arranged for the use of steam or compressed air, for instance, by substituting a cylinder for the solenoids 117 and 118 of Fig. 10 and adding a suitable valve or valves with control means preferably at the iron 55 which would be obvious to any person skilled in the art.

The drawings show a construction in which the ironing board is provided with legs, but any other construction can be adopted as, for instance, placing hinges on the board which are in turn secured to a wall or a small cupboard.

I claim as my invention:

1. An ironing device comprising an iron and an arm on which the iron is mounted, a supporting member for the arm, means for mounting the supporting member so that the arm may rotate horizontally and be movable vertically, a connecting member on the supporting member, and means cooperating with the connecting member to counterbalance the weight of the iron and arm and adapted when actuated to produce an ironing pressure on the iron when the iron is adjacent the material to be ironed.

2. An ironing device according to claim 1, in 75 which a casing is provided in which the sup-

porting member is slidably and rotatably mounted by means of ball bearings.

3. An ironing device comprising an iron and an arm on which the iron is mounted, a casing, a supporting member for the arm and projecting into the casing, ball bearings in the casing for slidably and rotatably supporting said member, a connecting member on the supporting member, means cooperating with the connecting member to counterbalance the weight 10 of the iron and arm and apply an ironing pressure on the iron when the iron is adjacent the material to be ironed, and means cooperating with the connecting member to maintain the ball 15 bearings in proper position.

4. An ironing device according to claim 3, in which an adjustment device is provided for the first-named means to adjust the application of the ironing pressure.

5. An ironing device comprising an iron and an arm on which the iron is mounted, an element for supporting said arm, a casing into which the element extends, mechanical means in the casing for counterbalancing the weight of 20 the iron and arm, and electrical means in the 25 casing for applying an ironing pressure to the iron when it has been moved adjacent the material to be ironed, said mechanical and electrical means operating through the element and arm. 30

6. An ironing device according to claim 5, in which means are provided to compensate for different thicknesses of material to be ironed whereby the ironing pressure is maintained constant irrespective of the thicknesses of the 35 materials to be ironed.

7. An ironing device according to claim 5, in which electrical means are provided to compensate for different thicknesses of material to be ironed whereby the ironing pressure is maintained constant irrespective of the thicknesses 40 of the materials to be ironed, said last-named electrical means including a switch which is closed after the compensating means has operated to then 45 energize the first-named electrical means.

8. An ironing device according to claim 5, in which means are provided to compensate for different thicknesses of material to be ironed whereby the ironing pressure is maintained constant irrespective of the thicknesses of the 50 materials to be ironed, said means including an electromagnet and a switch which is closed after the compensating means has operated to then 55 energize the first-named electrical means.

9. An ironing device comprising an iron and an arm on which the iron is mounted, and electrical means for counterbalancing the weight of the iron and arm, to apply an ironing pressure on the iron when the iron is adjacent the material to be ironed and to compensate for different 60 thicknesses of material.

10. An ironing device comprising an iron and an arm on which the iron is mounted, means for mounting the arm so that the iron and arm 65 may be rotated horizontally and moved vertically, means for counterbalancing the weight of the iron and arm and to apply an ironing pressure on the iron when the iron is adjacent the material to be ironed, and means for directing 70 a power medium to said first-named means to counterbalance and apply the ironing pressure.

11. An ironing device comprising an iron having a handle and an arm on which the iron is mounted, means for counterbalancing the weight 75

- of the iron and arm, electrical means for applying an ironing pressure on the iron when the iron is adjacent the material to be ironed, compensating means operated electrically to provide 5 uniform ironing pressure irrespective of the thickness of the material to be ironed, and means operable by the handle of the iron for closing an electric circuit to the electrical means and the compensating means.
- 16 12. An ironing device according to claim 11, in which the electrical and compensating means each include a separate electro-magnet.
13. An ironing device according to claim 11, in which the electrical and compensating means 15 each include a separate electro-magnet, and in which a controlling switch is provided in the arm operable by the handle to control the compensating means and the means for applying an ironing pressure.
- 20 14. An ironing device comprising an iron, an arm on which the iron is mounted so that it will be capable of being moved over an ironing board, a supporting member for the arm having a core secured thereto, two solenoids arranged 25 adjacent each other through both of which the core is adapted to pass, and means for energizing one of said solenoids to counterbalance the iron and arm when the iron is off the board and to apply an ironing pressure for the iron by the 30 other solenoid when the iron contacts the material on the board to be ironed.
15. An ironing device according to claim 14, in which the means includes an electric switch which is mounted in the arm adjacent the iron 35 and is operable by a handle on the iron.
16. An ironing device according to claim 14, in which a casing is provided in which the supporting member is slidably mounted and in which the solenoids are also mounted.
- 40 17. An ironing device according to claim 14, in which a casing is provided in which the supporting member is slidably mounted by means of ball bearings and in which the solenoids are 45 also mounted, and means being also provided to control the movement of the ball bearings to maintain them in proper positions.
18. An ironing device comprising an iron, an arm for mounting said iron so that it is capable 50 of being moved in horizontal directions over an ironing board, means for counterbalancing the weight of the iron and to apply an ironing pressure on the iron when the latter is adjacent the material to be ironed, said means being controlled from the iron, and means for directing a power 55 medium to said second-named means to operate the counterbalancing and ironing pressure means.
19. A mechanical device comprising a casing, a member movable relative to said casing, ball 60 bearings movably mounted between the casing and the member, a keeper for the ball bearings, and means to positively move the keeper on the member in the axial direction when the latter is moved axially relative to the casing which is 65 less than the distance moved by the member to maintain the ball bearings in proper positions between the casing and the member.
20. A mechanical device according to claim 19, in which the means includes a collar on the 70 movable member, a lever and a rod whereby the rod has one end connected to the keeper and the other end to the lever and the lever being guided in the collar.
21. A mechanical device according to claim 19, in which the means includes a pair of gear racks one on the movable member and one on the casting and a gear between these racks and meshing therewith.
22. A pressing machine comprising a pair of members one of which is movable and is provided with an ironing element and the other member being stationary, a link pivotally secured to the movable member, a spring having pivotal connections at the ends thereof one associated with the link and the other with one of the members, and means for shifting said link and spring together around one end as a pivot whereby in the contacting position of the members the spring will exert a pressing force and in the non-pressing and separated position of the members the spring will exert a counterbalancing force, said link having means to effect a uniform floating action of counter balance force throughout the entire movement of the movable member.
23. A pressing machine according to claim 22, in which the means of the link comprises a short lever one end of which is connected to the link the other end connected to the end of the spring associated with the link.
24. A pressing machine comprising a movable member and a stationary member, the movable member having a pivotally mounted arm and an ironing element secured on said arm being movable relative to the other member, a link pivotally connected at one end to the movable member, a spring connected at one end to the link, means at the other end of the link to connect the other end of the spring with the stationary member, and means for shifting the link and spring when the ironing element contacts the stationary member so that the spring will exert a pressing force and when said movable member is moved relative to the stationary member the spring exerting a counterbalance force by said first-mentioned means to impart a uniform floating action throughout the entire travel 40 of the movable member.
25. A pressing machine comprising a movable member and a stationary member, the movable member having an ironing element thereon being movable relative to the other member, a link pivotally connected at one end to the movable member, a spring connected at one end to the link, a compensating device at the other end of the link in the form of two short levers one 50 of which connects the link with the other end of the spring and the other lever connects the link with the stationary member, and means for shifting the link and spring when the ironing element contacts the stationary member so that the spring will exert a pressing force and when said movable member is moved relative to the stationary member the spring exerts a counter-balancing force which is compensated by the device to impart a uniform floating action throughout the entire travel of the movable member.
26. A pressing device according to claim 25, in which the pair of short levers are integral with each other.
